CLAIM

The ornamental design for a battery charger for earphones, as shown and described.

DESCRIPTION

FIG. 1 is a front, top, right side perspective view of a battery charger for earphones;

FIG. 2 is a rear, top, left side perspective view of the battery charger for earphones;

FIG. 3 is a front elevational view of the battery charger for earphones;

FIG. 4 is a rear elevational view of the battery charger for earphones;

FIG. 5 is a top plan view of the battery charger for earphones;

FIG. 6 is a bottom plan view of the battery charger for earphones;

FIG. 7 is a right side elevational view of the battery charger for earphones;

FIG. 8 is a left side elevational view of the battery charger for earphones; and,

FIG. 9 is a front, top, right side perspective view of the battery charger for earphones shown in a state of use.

The dashed broken lines in the drawings depict portions of the battery charger for earphones that form no part of the claimed design. The dot-dot-dashed lines showing earphones in FIG. 9 depict environment and forms no part of the claimed design.

1 Claim, 9 Drawing Sheets
